DESIGN FOR AN AUTOMATIC TELEGRAPH DEVICE

Robert D. Parrott, West New York, and Raleigh J. Wise, Dunellen, N. J., assignors to The Western Union Telegraph Company, New York, N. Y., a corporation of New York

Application September 14, 1942, Serial No. 108,225

Term of patent 14 years

To all whom it may concern:

Be it known that we, Robert D. Parrott and Raleigh J. Wise, citizens of the United States, residing at West New York and Dunellen, respectively, in the counties of Hudson and Middlesex, and State of New Jersey, have invented a new, original, and ornamental Design for an Automatic Telegraph Device, of which the following is a specification, reference being had to the accompanying drawing, forming part thereof.

The figure is a perspective view of an automatic telegraph device, showing our new design.

The side of the automatic telegraph device not shown is substantially the same as the side shown in the figure, and the rear wall is plain.

We claim:

The ornamental design for an automatic telegraph device, as shown and described.

ROBERT D. PARROTT.
RALEIGH J. WISE.
